UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

DESIGN FOR A RANGE

Application filed January 14, 1932. Serial No. 42,482. Term of patent 14 years.

To all whom it may concern:

Be it known that I, WILLIAM D. ANTRIM, a citizen of the United States, residing at Gloucester, Camden County, New Jersey, have invented a new, original, and ornamental Design for a Range, of which the following is a specification, reference being had to the accompanying drawings, forming part thereof, in which:

Figure 1 is a perspective view of a range embodying my new design; and

Fig. 2 is a sectional plan view of the front of the range, on the line 2—2, Fig. 1.

I claim:

The ornamental design for a range, substantially as shown.

WILLIAM D. ANTRIM.
